UNITED STATES PATENT OFFICE.

PAUL A. SCHUCHART, OF BROOKLYN, NEW YORK, ASSIGNOR, BY DIRECT AND MESNE ASSIGNMENTS, TO PAPER SERVICE CO., INC., A CORPORATION OF NEW YORK.

SHEET-INTERFOLDING MACHINE.

1,228,835.

Specification of Letters Patent. Patented June 5, 1917.

Application filed February 28, 1914. Serial No. 821,796.

To all whom it may concern:

Be it known that I, PAUL A. SCHUCHART, a subject of the Crown of Austria, and resident of the borough of Brooklyn, in the city 5 and State of New York, have invented a new and useful Improvement in Sheet-Interfolding Machines, of which the following is a specification.

This invention relates to an improvement 10 in machines for cutting, reversely creasing, superposing and overlapping sheets, and includes novel means for delivering the sheets in a continuous interfolded stack.

A practical embodiment of my invention 15 is represented in the accompanying drawings, in which—

Figure 1 represents a side elevation of a machine for cutting, reversely creasing, superposing and overlapping sheets cut 20 from different webs and delivering the same in a continuous interfolded stack,

Fig. 2 represents a vertical longitudinal section through the same,

Fig. 3 represents in detail a modified form 25 of oscillating delivery device,

Fig. 4 represents a detail horizontal section through the guides for the delivery device,

Fig. 5 represents a diagrammatical view 30 of the sheets in their cut, reversely creased, superposed and overlapped position, and

Fig. 6 represents a diagrammatical view of the sheets showing the position they assume when folded in a stack.

35 The side frames of the machine are denoted by 1, 2. The webs 3, 4, are fed from a suitable source of supply (not shown) between feed rollers 5, 6, to the rotary coacting cutting and creasing cylinders 7, 8, 40 mounted to rotate in the frames. The cylinder 7 is provided with cutting blades 9 and creasing blades 10 which are alternately secured therein, and coact with blocks 11, 12, respectively, located in the cylinder 8, for 45 alternately cutting and creasing the webs as they pass therethrough.

The webs 13, 14, are fed from a suitable source of supply (not shown) between feed rollers 15, 16, to their rotary coacting cutting and creasing cylinders 17, 18. The cylinder 17 is provided with cutting blades 19, and creasing blades 20, which coact with blocks 21, 22, respectively, located in the cylinder 18.

55 The webs 3, 4, 13, 14, entering from oppo-

site directions will meet and pass downwardly between the cylinders 8 and 18, which are so arranged as to hold the webs firmly between them, while they are being alternately cut into sheets 23, 24. The cutting and creasing blades on both the cylinders 7 and 17 are arranged so that when the blade 9 on the cylinder 7 is cutting the sheets from the webs 3, 4, the creasing blade 20 on the cylinder 17 is creasing the webs 13, 14; when the cutting blade 19 on the cylinder 17 is cutting the webs 13, 14, the creasing blade 10 on the cylinder 7 is creasing the webs 3, 4. Thus it will be seen that by this alternately cutting and creasing of 60 the webs and feeding them to one course, they are brought together in a continuous superposed overlapping and reversely creased position, as shown in Fig. 5.

The superposed sheets 23, 24, pass downwardly through vertical air extracting guides 25, 26, to an oscillating delivery device comprising a pair of upper rolls 27, 28, oscillating lower rolls 29, 30, and tapes 31, 32, passing over the said rolls.

The lower roll 29 is independently supported by swinging arms 33, 34, mounted on the shaft 35, of the upper roll 27, and the roll 30 is independently supported by swinging arms 36, 37, mounted on the shaft 38 of 80 the upper roll 28. The tapes and the lower rolls are yieldingly held in engagement by means of springs 39 secured to the swinging arms.

The sheets after passing from the oscillating delivery rolls 29, 30, are delivered in a continuously interfolded stack in a delivery box 40, as shown separated in Fig. 6, and are held in this overlapped position within the delivery box 40 by means of a 90 pair of retainers 41, 42, pivoted to the top of the box at 43. These retainers are alternately raised to permit the sheets to enter the box by means of upwardly projecting arms 44, 45, carried by the retainers 41, 42, 95 which arms are engaged by the rolls 29, 30, in their oscillatory movement.

The means for oscillating the swinging arms with their rollers is as follows: The drive shaft 46 is provided with an eccentric and strap connection 47, which is adjustably secured to the free end of a rocking arm 48 fixed to the shaft 49, mounted in the side frames 1, 2. Depending from the shaft 49 outside the frames are a pair of 105

arms 50, 51, which are connected to the swinging arms 36, 37, by links 52, 53.

The upper rolls 27, 28, are driven from the shaft 46 through a gear 54 meshing with gear 55 fixed on shaft 38 of the roll 28 and a gear 56 fast on the shaft 35 of the roll 27.

The cylinders 17, 18, and feed rolls 15, 16, are driven from the gear 54 through a train of gears 57, 58, 59, 60 and 61, and the cylinders 7, 8, and the feed rolls 5, 6, from the gear 57 through a train of gears 62, 63, 64, 65 and 66.

To direct the sheets downwardly between the cylinders 8 and 18, I provide a guide 67 fixed to the frames 1, 2, and located between the cylinders 8 and 18.

To extract the air from the sheets as they pass between the vertical guides 25, 26, downwardly to the rolls 27, 28, I provide 20 the faces of these guides with vertical channels 68, the upper end of which is open and the lower end closed. Near the lower end in each channel there is located a hole 69 leading into the chamber 70 which has pipes 71, 25 72, passing to the outside of the machine.

Owing to the speed at which the paper passes from the cylinders 8, 18, to the oscillating delivery, it has been found that the air should be withdrawn from the paper as 30 it passes through the guides.

The friction between the paper and the air passing through the guides so constructed, will cause the air to pass down the channels 68, through the holes 69, into the chamber 70 and escape through the pipes 71, 72, to the outside of the machine.

In the modified form of oscillating delivery device shown in Fig. 3, the lower rolls are supported in a swinging frame 73 pivoted at 74 to the side frames and they are oscillated in the same manner as shown in Figs. 1 and 2. The tapes 31*, 32*, are provided with take-up rolls 75, 76, mounted in swinging arms 77, 78, pivoted in the side frames. The rolls are provided with springs 79, 80, to keep the tapes at the proper tension at all times.

In operation, the webs are fed into the feed rolls from both ends of the machine, 50 passing through the cutting and creasing cylinders, assembled in superposed relation between the cylinders 8 and 18; thence in a downward path through the air extracting guides; and thence through the oscillating 55 tape carrier to be deposited into the delivery box in a continuous overlapped and interfolded stack.

The stack is held in position in the box by the retainers, which are alternately lifted 60 by the oscillating movement of the rolls to receive each series as it is laid thereon.

While I have described two webs as being introduced into each side of the machine, it is to be understood that one or more may 65 be introduced as found desirable.

It is evident that various changes may be resorted to in the form, construction and arrangement of the several parts without departing from the spirit and scope of my invention; hence I do not wish to limit myself strictly to the structure herein set forth, but

What I claim is:—

1. The combination with a machine for reversely creasing, superposing and overlapping sheets cut from different webs, of a pair of coacting rotary delivery rolls, means for oscillating the rolls for delivering the sheets in a continuous interfolded stack and a pair of retainers for the top of the stack operated by said rolls to alternately engage the 80 stack.

2. The combination with a machine for reversely creasing, superposing and overlapping sheets cut from different webs, of a pair of coacting rotary delivery rolls, a swinging 85 support for said rolls to cause them to deliver the sheets in a continuous interfolded stack and a pair of retainers for the top of the stack operated by said rolls to alternately engage the stack.

3. The combination with a machine for reversely creasing, superposing and overlapping sheets cut from different webs, of a pair of coacting endless tape carriers, and means for oscillating the delivery end of 95 the tape carriers for delivering the sheets in a continuous interfolded stack.

4. The combination with a machine for reversely creasing, superposing and overlapping sheets cut from different webs, of a pair of coacting endless tape carriers, means for oscillating the delivery end of the said tape carriers for delivering the sheets in a continuous interfolded stack, and a pair of 100 retainers for the top of the stack operated by said tape carriers to alternately engage the stack.

5. The combination with a machine for reversely creasing, superposing and overlapping sheets cut from different webs, of a device for delivering the sheets in a continuous interfolded stack comprising upper and lower pairs of rolls, tapes passing over said rolls, means for oscillating the lower pair of rolls, and a pair of retainers for the top 115 of the stack operated by said device to alternately engage the stack.

6. The combination with a machine for reversely creasing, superposing and overlapping sheets cut from different webs, of a device for delivering the sheets in a continuous interfolded stack comprising upper and lower pairs of rolls, tapes passing over said rolls, means for oscillating the lower pair of rolls, and means for yieldingly holding 120 the lower rolls together.

7. The combination with a machine for reversely creasing, superposing and overlapping sheets cut from different webs, of a device for delivering the sheets in a continu- 125

ous interfolded stack comprising upper and lower pairs of rolls, tapes passing over said rolls, means for oscillating the lower pair of rolls, and means for yieldingly holding the lower rolls together, and a pair of retainers for the top of the stack operated by said device to alternately engage the stack.

8. The combination with a machine for reversely creasing, superposing and overlapping sheets cut from different webs, of a device for delivering the sheets in a continuous interfolded stack comprising upper and lower rolls, tapes passing over said rolls,

means for oscillating the lower rolls about the axes of their respective upper rolls, and 15 a pair of retainers for the top of the stack operated by said lower rolls.

In testimony, that I claim the foregoing as my invention, I have signed my name in presence of two witnesses, this eleventh day 20 of February 1914.

PAUL A. SCHUCHART.
